UNITED STATES PATENT OFFICE.

HARRY E. McCOY, OF PITTSBURGH, PENNSYLVANIA.

RACING TOY.

Application filed March 14, 1925, Serial No. 15,500. Renewed November 17, 1925.

This invention relates to toys or games in which objects are caused to move in simulation or representation of racing figures.

The invention relates generally to toys 5 of the same general type as those disclosed in my co-pending applications Serial No. 690,264, filed February 2, 1924, and Serial No. 710,010, filed April 30, 1924, and also application Serial No. 15,499, filed the same 10 day as the present application.

In all of said applications, a horizontal shaft is provided which has cranks or eccentrics thereon, to which are connected miniature racing objects, such as toy horses. 15 Means are provided for rotating the shaft, whereby a bobbing motion, suggestive of running, is imparted to the objects.

In the first of the above-mentioned applications, the shaft also moves in a circle, 20 so that the racing objects move in circular paths while bobbing up and down. In the last application above mentioned, the shaft also travels in a circle, but the horses move over a surface revolving in the opposite 25 direction. In the second of the above applications, the shaft is supported in a stationary bearing, so that the racing objects merely bob up and down.

The present invention relates to toys 30 more nearly like those of the first and last applications, in that the shaft may revolve about a fixed center, but only through a limited arc. The arrangement is such that, with the shaft rotating at comparatively high speeds, the movement of the shaft through its arc about the fixed pivot creates the appearance of a close race, and provides an extremely attractive and novel toy.

The nature of the invention may be readily understood by reference to the accompanying drawings, in which:—

Fig. 1 is a top plan view of the toy;

Fig. 2 is a side elevation, showing a part of the pan broken away; and

Fig. 3 is a detail view of the releasing device.

In the drawings, 5 designates a suitable base, preferably in the form of a pan, having a rim or flange 5^e of appreciable height.

50 Eccentrically disposed in the pan is a vertical pin 6 on which is hung a sleeve 7, whose lower end carries a centrally apertured spinning disk 8, the pin and sleeve providing a spindle type bearing for the disk. Surrounding the sleeve is a suitable

collar or double ring construction 9 which serves as an anchor and support for a horizontally extending shaft 10 in which are cranks or eccentrics 11. Near the inner end of the shaft is a friction wheel 12 that rests 60 on the disk 8, and serves both to rotate the shaft when the disk is rotated and to support the inner end of the shaft.

The outer end of the shaft rests on the rim of the pan or base. Rotatably connected 65 with each crank, preferably by its front legs or other suitable extensions, is a miniature figure 13, as a horse or other suitable racing object, with its rear portion, such as its rear legs, trailing on the bottom of the pan. 70

When the spinning disk is rotated, as by sharply twisting the sleeve 7, the rotating movement imparted to the shaft causes the horses to move up and down, giving the action or appearance of racing horses. At the 75 same time, the revolving end of the shaft, resting on the pan, will give a slow traveling motion to the shaft, causing the shaft to swing in an arc about its anchorage on the sleeve. 80

Inasmuch as the spinning disk is eccentric with respect to the base, the arc through which the shaft may then travel is necessarily limited, and such movement is further confined between starting and stopping devices 14 and 15, respectively, these devices fixing the start and finish points of the race. 85

The starting device 14 is shown in detail in Fig. 3. It consists of a sheet metal arm 14, pivoted at 16, and having a downwardly 90 hooked extension 17 thereon, adapted to swing down over the end of the shaft. When thus engaged with the shaft, this device will allow the shaft to rotate freely, but will hold it against travel toward the stop 95 15.

The stop includes the fixed hook 15 directed toward the starting member and having a transverse lug 18 projecting therefrom. 100

On the shaft 10 is a wheel 19 having hook-like teeth thereon, preferably corresponding in number and position to the several cranks on the shaft. When, in its traveling movement, the shaft reaches the 105 hook 15, one of the teeth of wheel 19 will hook over lug 18, thus stopping rotation of the shaft, and at the same time preventing further forward movement thereof.

In playing a game with the toy, it is pro- 110

posed that the start 14 be initially engaged to hold the shaft against travel until the disk has been spun. The player then releases the start member 14, and the rotating shaft slowly travels toward stop 15. When it engages the stop, the horse which is furthest forward is the winner. For example, in Fig. 1, if the inner horse were in the position shown in Fig. 1 when the shaft (which is at the starting point) reached the finish, it would be the winner, while the middle horse would be the last at the finish. The object of the toothed wheel is to cause the shaft to stop rotation in such manner that the winning horse can be easily determined, as the teeth of the wheel will be arranged with definite relation to the cranks, so that, when a tooth engages the lug, the crank in corresponding position to the tooth will be furthest forward.

The spinning disk may have indicating pointers 2 thereon, while game point designations A may be applied to the base, so that, when the toy is used as a game, definite points may be scored by the several players.

Various detail changes may be made in the construction of the toy, and the arrangement of parts, within the contemplation of my invention, and under the scope of the appended claims.

I claim as my invention:—

1. A toy including a base having an upright flange thereon, a shaft pivotally and rotatably anchored at one end above the base, the other end of the shaft resting on said flange, a series of cranks on the shaft, miniature racing objects connected with the cranks, and means for rotating the shaft.

2. A toy including a base having an upright flange thereon, an upright stem eccentrically positioned on the base, a shaft rotatably and pivotally connected with the stem, cooperating means associated with the stem and shaft for rotating the latter, eccentrics on the shaft, racing objects engaging the eccentrics and having a portion thereof resting on the base, the outer end of the shaft resting on the said flange.

3. A toy comprising a base having a flange thereon, a horizontal spinning disk on the base, a horizontal shaft rotatably and pivotally supported above the base with its outer end on the flange, a friction wheel on the shaft engaging the disk for effecting rotation of the former when the latter is spinning, starting and stopping abutments on the flange between which the shaft may move, said shaft having eccentrics thereon, and racing objects resting on the base having por-

tions thereof operatively connected with the eccentrics.

4. A toy comprising a base having a flange thereon, a horizontal spinning disk on the base, a horizontal shaft rotatably and pivotally supported above the base with its outer end on the flange, a friction wheel on the shaft engaging the disk for effecting rotation of the former when the latter is spinning, starting and stopping abutments on the flange, between which the shaft may move, said starting abutment comprising a member pivoted to said flange and having a hook thereon adapted to swing into and out of shaft engaging position, whereby the shaft may be rotated while confined against swinging movement by said abutment, said shaft having eccentrics thereon, and racing objects resting on the base having portions thereof operatively connected with the eccentrics.

5. A toy comprising a base having a flange thereon, a horizontal spinning disk on the base, a horizontal shaft rotatably and pivotally supported above the base with its outer end on the flange, a friction wheel on the shaft engaging the disk for effecting rotation of the former when the latter is spinning, starting and stopping abutments on the flange between which the shaft may move, said stopping abutment comprising a hook beneath which said shaft may travel for a limited distance and having a lug thereon, said shaft having a wheel thereon with hook-like teeth adapted to engage the lug to arrest rotation of the shaft by engagement therewith, said shaft also having eccentrics thereon, and miniature racing objects each having a portion thereof dragging on the base and another portion operatively connected with an eccentric.

6. A toy comprising a base having a flange thereon, a horizontal spinning disk on the base, a horizontal shaft rotatably and pivotally supported above the base with its outer end on the flange, a friction wheel on the shaft engaging the disk for effecting rotation of the former when the latter is spinning, starting and stopping abutments on the flange between which the shaft may move, said shaft having eccentrics thereon, and racing objects resting on the base having portions thereof operatively connected with the eccentrics, said stopping abutment including a lug, and a toothed wheel on the shaft having teeth thereon arranged to engage the lug to arrest rotation of the shaft.

In testimony whereof I affix my signature.
HARRY E. McCOY.
